UNITED STATES PATENT OFFICE.

HENRY DAVIS, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 14,059, dated July 10, 1883.

Application filed June 1, 1883. Term of patent 3½ years.

To all whom it may concern:

Be it known that I, HENRY DAVIS, of Brooklyn, Kings county, New York, have invented a new and original Design for Carpets, of 5 which the following is a specification.

This invention relates to a new and original design for carpets and similar fabrics; and it consists in the novel grouping and configuration of figures hereinafter more fully described.

10 The accompanying drawing illustrates a face view of a carpet having my new design.

The design presents an open, regular, and quiet appearance, and is clearly shown in the drawing.

I claim—

15 The design for a carpet, consisting of the design substantially as shown and described.

HENRY DAVIS.
